UNITED STATES PATENT OFFICE.

WILLIAM A. ALEXANDER, OF WILKINSBURG, PENNSYLVANIA.

FAUCET, SPIGOT, AND COCK.

981,349.

Specification of Letters Patent. Patented Jan. 10, 1911.

Application filed April 21, 1910. Serial No. 556,764.

To all whom it may concern:

Be it known that I, WILLIAM A. ALEXANDER, a citizen of the United States of America, residing at Wilkinsburg, in the county 5 of Allegheny and State of Pennsylvania, have invented certain new and useful Improvements in Faucets, Spigots, and Cocks, of which the following is a specification, reference being had therein to the accompanying drawing.

This invention relates to faucets, spigots, and cocks, and the object of my invention is to provide a faucet with means as will be hereinafter set forth for opening and closing a faucet without subjecting the valve seat to a grinding action, or the necessity of removing the valve stem to repair the valve.

Another object of this invention is to provide a faucet with a novel valve that will be positive in its action, free from injury by ordinary use, and highly efficient for controlling the passage of water or other fluid through the faucet.

A further object of this invention is to 25 provide a simple and durable valve that can be used in connection with various types of faucets, easily removed, renewed or repaired.

With these and such other objects in view as may hereinafter appear the invention consists of the novel construction, combination and arrangement of parts to be hereinafter 30 specifically described and then claimed.

Reference will now be had to the drawings forming a part of this specification, 35 wherein there are illustrated the preferred embodiments of the invention, but it is to be understood that the structural elements thereof can be varied or changed, as to the size, shape, and manner of assemblage without departing from the scope of the invention.

In the drawings: Figure 1 is a vertical longitudinal sectional view of a faucet in accordance with my invention. Fig. 2 is a 45 front elevation of the same showing the outlet piece or spout removed and the resilient valve supporting arm in cross section. Fig.

3 is a horizontal sectional view of the faucet. Fig. 4 is a front elevation of the faucet. Fig. 50 5 is a similar view of a double faucet in accordance with my invention. Fig. 6 is a cross sectional view of the same, and Fig. 7 is a horizontal sectional view of the double faucet.

In the accompanying drawings the reference numeral 1 denotes a globular faucet body provided with a rearward extension 2 terminating in an exteriorly threaded nipple 3 to which is adapted to be connected a supply pipe (not shown). The body 1 is provided with an L-shaped partition 4 having the horizontal portion thereof provided with an opening 5 and a valve seat 6.

7 denotes a nose at the forward end of the valve body and 8 a bonnet, said bonnet 65 having the interior walls thereof threaded, as at 9, for an exteriorly screw threaded head 10 carried by a valve stem 11, the stem 11 having a depending portion 12 below the head 10. The stem 11 extends upwardly 70 through a stuffing box or cap 13 detachably mounted upon the bonnet 8, and the upper end of the stem is provided with the usual form of handle 14.

15 denotes an outlet piece or spout 75 adapted to be connected to the nose 7, said outlet piece or spout having oppositely disposed apertured lugs 16 detachably connected to similar lugs 17, carried by the nose 7 by set screws or other fastening means 18. 80

19 denotes a resilient valve supporting arm having the forward end thereof secured to the inner upper side of the outlet piece or spout 15 by a set screw or other fastening means 20. Connected to the inner 85 or rear end of the arm 19 is a valvular member 21 and detachably connected to the lower end of said member by a set screw 22 is a flexible washer 23.

A faucet constructed as above described is 90 operated in the following manner. By rotating the stem 11 to screw the head 10 inwardly, the depending portion 12 of the stem impinges the inner or rear end of the resilient arm 19 and the washer 23 is caused 95 to engage the seat 6 and close the opening 5. To open the faucet the valve stem 11 is rotated in the opposite direction and as the depending portion 12 is raised, the resiliency of the arm 19 immediately elevates the 100 washer 23.

In Figs. 5 to 7 inclusive there is shown a double faucet designed for use in connection with bath-tubs, basins, etc., and the faucet has the ends thereof provided with 105 detachable outlet pieces or spouts 24 supporting the arms 19. In this instance the outlet pieces or spouts are threaded upon

the ends of the faucets, and can be secured in a manner similar to the outlet piece or spout 15.

What I claim, is:

- 5 1. In a faucet, a detachable outlet piece, a resilient arm carried by said piece and extending into said faucet, and a valvular member carried by the inner end of said arm and adapted to close said faucet, said 10 arm tending to hold the valvular member in position to open the faucet.
2. In a faucet, an outlet piece, a resilient arm carried by said outlet piece and extending into said faucet, a valvular member 15 carried by the inner end of said arm and adapted to close said faucet, said arm tend-

ing to hold the valvular member in position to open the faucet, and a valve stem adapted to move said member to a closed position.

3. In a faucet, a resilient arm extending 20 into said faucet, a valvular member carried by said arm and adapted to close said faucet, said arm tending to hold the valvular member in position to open the faucet, and means adapted to detachably hold said arm 25 in engagement with said faucet.

In testimony whereof I affix my signature in the presence of two witnesses.

WILLIAM A. ALEXANDER.
